UNITED STATES PATENT OFFICE

NICOLAY K. FOUGNER, OF NEW YORK, N. Y.

SAFETY RAZOR

Application filed November 23, 1931. Serial No. 576,886.

This invention relates to safety razors, and has particular reference to a safety razor having a continuous blade.

The invention aims for one of its objects 5 to provide a razor of the type specified, in which the blade holder is fashioned to form a closed hollow handle part constituting a container for blade supply and receiving spools, and to further form a guard part 10 defining a pair of spaced flat surfaces for simultaneously supporting for shaving, two separate lengths of the blade.

The invention further comprehends in a 15 blade holder for a continuous blade safety razor, a clamping element carried by and shiftable with respect to the guard part of the holder to releasably clamp the two active or exposed lengths of the blade between said element and the surfaces of the guard.

20 As a further feature, the invention embodies a continuous blade for safety razors having a longitudinal cutting edge and which is adapted to be coiled on a flanged spool, which blade is so constructed as to provide 25 means for spacing the cutting edge from the flanges of the flanged spool.

The invention further comprehends a spool 30 for a continuous blade, in which the spool is so constructed as to cooperate with the blade to avoid contact of the cutting edge with the spool flange.

Other objects of the invention reside in a 35 safety razor of the indicated character which employs but few and simple parts capable of economical production and assemblage and which is highly efficient in its purpose.

Other objects will be apparent from the 40 following description and accompanying drawings, while the actual scope of the invention is defined by the appended claims.

In the drawings:

Figure 1 is a top plan view of a safety 45 razor constructed in accordance with the invention.

Figure 2 is a side or edge view thereof.

Figure 3 is a bottom plan view thereof.

Figure 4 is an enlarged inverted sectional 50 plan view taken approximately on the plane indicated by the line 4-4 in Figure 2.

Figure 5 is an enlarged longitudinal sec-

tional view taken approximately on the plane indicated by the line 5-5 in Figure 1.

Figure 6 is a fragmentary view similar to 55 Figure 5, illustrating the released condition of the blade.

Figure 7 is an enlarged transverse sectional view taken approximately on the line 7-7 of Figure 1.

Figure 8 is an inverted plan view of the 60 manipulator for turning the blade receiving spool.

Figure 9 is an enlarged longitudinal section view of the blade clamping element.

Figure 10 is an enlarged longitudinal section view of the upper section of the blade 65 holder casing.

Figure 11 is a similar view of the lower section of the blade holder casing.

Figure 12 is a perspective view of one of 70 the blade spools.

Figure 13 is an edge view of one of the blade spools.

Figure 14 is a fragmentary side view of one end of the blade.

Figure 15 is a detail perspective view of the 75 pawl which cooperates with the blade spool ratchet teeth.

Figure 16 is an inverted plan view of a modified form of the manipulator for turning the blade receiving spool.

Figure 17 is a plan view of a modified 80 form of blade spool.

Figure 18 is a side or edge view with parts 85 broken away and shown in section, and illustrating a modified form of the blade holder construction.

Referring to the drawings by characters of reference, the razor includes a continuous blade 20 having a longitudinal cutting edge 21 and provided at its opposite ends with terminals 22 which are of greater width than the width of the remaining portion of the blade and which have edges 23 extending beyond the cutting edge 21. The terminal strips 22 in addition to constituting means for handling the blade to avoid cutting of the fingers, are provided with suitable means, such as a keyhole slot 24, for interengagement with a headed stud 25 on the tubular body 26 of a spool. As illustrated, the termi-

55

70

75

80

95

100

nal strips 22 correspond in width approximately to the length of the tubular body, and said tubular body is provided at its opposite ends with the annular flanges 27 and 28.

5 The blade holder comprises upper and lower sections 30 and 31, which when assembled define a closed hollow handle part 32 which is adapted to act as a magazine for and contain the unused and used lengths of 10 the blade 20. The upper section also defines an extending guard part 33 which is of substantially channel shaped cross sectional configuration, presenting a continuous depending marginal flange 34 defining a pair of 15 spaced flat longitudinally converging surfaces 35 and 36 joined at their outer ends by a curved, preferably arcuate, connecting surface 37, the radius of which is approximately equal to that of the spool body radius. The 20 lower edges of the portions of the flange 34 defining the flat surfaces 35 and 36 are notched to provide the guard teeth 40, while the surfaces 35, 36 and 37 at the upper portion of the flange are provided with an outwardly projecting bead 41 defining an abutment shoulder 42 against which the upper edge of the blade is designed to seat. The 25 upper section 30 of the blade holder is provided with a depending tubular boss 44 which 30 has an interiorly threaded lower end 45, and which boss extends into an opening 46 in the lower section 31 and terminates within said opening. The upper section 30 is also provided with an arcuate depending wall 47 at 35 its juncture with the guard part 33, and depending blade guiding flanges 48 and 49 extending rearwardly from said wall 47.

The lower section 31 of the holder is formed 40 with an upstanding wall 50 extending around one end and along the opposite sides thereof and terminating adjacent the depending arcuate wall 47. The terminals of the walls 50 are spaced from the blade guiding flanges 48 and 49 a distance approximating the 45 thickness of the blade 20, thereby defining passages 51 and 52 through which the blade passes from and is returned to the hollow handle part 32. Obviously, the easing sections 30 and 31 may be assembled in any desired manner, such as by the interengagement 50 of the tongues 53 at the upper edge of the wall 50 with the receiving notches 54 at the marginal edges of the upper section 30, and said sections may be removably retained 55 in assembled relation by the screw 55, the threaded shank 56 of which engages with the internal thread 45 of the depending tubular boss 44. The screw 55 is preferably provided with a kerf 57 of a size to accommodate a coin so as to avoid the necessity of using a 60 screw driver to remove or emplace the screw. The depending tubular boss 44 is circular in cross section and is of an appropriate size to constitute a journal for receiving thereon the spool body 26 from which the blade extends 65

through the passage 51 around the surfaces 35, 36 and 37 and is thence returned through the passage 52. The screw 55 also serves as a means for setting up a resistance or retarding action to the free turning of the supply spool, which resistance may be varied by tightening or loosening the screw to cause variation in the clamping of the casing walls against the spool flanges.

70 The upper section 30 is provided with an opening 60 of larger size than but disposed in axial alignment with an opening 61 in the bottom section 31. The opening 60 accommodates the circular bearing portion 62 of a spool mounting and turning assemblage 63 formed with an exteriorly disposed circular head part 64. The member 63 further includes a reduced cylindrical portion 65 which is of a diameter to snugly receive and accommodate thereover the tubular body 26 of a blade spool. The assemblage 63 further includes a shank 66 projecting axially from the reduced portion 65 and formed with a threaded extremity 67. A retaining screw 68 having a reduced cylindrical portion 69 is designed to engage through the opening 61 in the lower section and to snugly engage within the spool body 26. The shank 69 is formed with a threaded recess 70 for receiving the threaded terminal 67, while the enlarged head 71 of the screw 68 engages over the lower outer surface of the lower section 31 around the opening 61 and is provided with a kerf 72 corresponding to the kerf 57 of the screw 55. The portion 62 of the member 63 is provided with circumferentially spaced depending coupling lugs 73 and the spool flange 28 is provided with correspondingly formed openings 74 to receive the coupling lugs 73, whereby the spool is mounted and connected for turning movement by and with the manipulator part 64.

75 In order to prevent retrograde movement of the spools, the flanges 28 of the same are formed with peripheral ratchet teeth 75 with which the arms 76 and 77 of a double spring pawl 78 cooperate. The pawl is preferably constructed from a single piece of material having a medial angulated projecting portion 79 which is anchored in a receiving slot 80 in the upper section 30.

85 In order to provide means whereby the user may observe the amount of blade remaining on the supply spool, the lower flange 27 is formed of celluloid or any other suitable transparent material, while the front wall of the lower casing section 31 is provided with a window opening 81 within which is arranged a celluloid or transparent panel 82.

90 The portion of the blade 20 having the longitudinal cutting edge 21 lying between the terminals 22 may tend to sag and contact with the lower flange 27, thereby resulting in dulling of the cutting edge. In order to 95

overcome this, the upper or unsharpened edge of the strip 20 is caused to adhere to the upper flange 28 in any desired manner, preferably by forming said flange 28 as a permanent magnet consisting of a plurality of circumferentially spaced magnetized sections 83. It may also be found desirable to coat the upper surface of the lower flange 27 with a suitable transparent grease or lubricant L, as illustrated in Figures 5 and 6 of the drawings, for the purpose of protecting the cutting edge against the possibility of oxidation. Obviously, as the blade is withdrawn from the hollow handle part, the grease or lubricant will be substantially removed by its movement through the passage 51 and, further, by flushing the blade with hot water. The razor further includes a clamping element designated generally by the reference character 85. The clamping element is shaped to conform generally to the guard part of the upper section 30 and is provided with a depending marginal flange 86. The lower beveled edges 87 of the portions which are designed to lie alongside of the surfaces 35 and 36 terminate slightly above the cutting edge of the blade. The remaining portion corresponding to the curved or arcuate surface 37 protrudes downwardly as at 88 and is provided with an inwardly directed bead 89 which engages under that portion of the guard part 33 which is provided with the surface 37. The flange 86 on its inner surface adjacent its juncture with the clamping element 85 is formed with a continuous groove 90, to insure a clearance for proper clamping action of the lower part of the flange with the blade. The guard element 85 is formed with a longitudinal slot 91 and the guard part 33 is provided with an up-standing T-shaped rib 92, the shank of which extends through the slot 91 and the head of which overlies the guard element to act as a guide for longitudinal shifting of the guard element respectively to the clamped and released positions illustrated in Figures 5 and 6. In order to provide means for facilitating the shifting of the guard element and for locking the same in its clamped relation, a knob 93 is carried by a spindle 94 which is journaled in a bearing opening 95 in the element 85, and said spindle carries at its lower end an eccentric or double cam locking element 96 which is received within the tubular boss 44 and coacts therewith, as illustrated in Figure 5, to lock the locking element in clamped relation to the blade and to act as a final means for drawing the clamping element tightly against the blade. In order to facilitate flushing and cleansing of the blade, guard part and clamping element when the blade is released, the said clamping element is formed adjacent its juncture with the flange 86 with a plurality of slots 97. It thus follows that after the

shaving operation with the clamping element moved to the release position illustrated in broken lines in Figure 1, a free passage is afforded between the guard part and flange of the clamping element by virtue of the slots 97. After flushing, a rapid shaking will dislodge the water from the blade and blade holder.

If desired, as illustrated in Figures 16 and 17 of the drawings, the spool mounting member and spool flange may be provided with coupling projections and recesses 98 and 99 which are of a configuration to form a trade name or other identifying indicia, to insure to the user the replacement of a genuine blade corresponding to the type of holder provided.

In use, the hollow handle part 32 serves as a means for grasping the device in the hand when shaving with the section 30 disposed uppermost, thereby disposing the blade in approximately parallel relation to the face. Due to the fact that two lengths of the blade are exposed for use simultaneously, it is obvious that the razor may be used in either the right or left hand with equal facility. As soon as the cutting efficiency of the exposed lengths is impaired, the user has only to turn the knob 93 to release the cam from engagement with the boss 44 and to then shift the clamping element 85 from the full line to the dotted line position shown in Figure 1. This releases the blade and the user then turns the assemblage 63 in a clockwise direction to withdraw from the hollow handle part 32 a new length of blade from the supply spool which is journaled on the tubular boss 44. At the same time, this winds onto the other receiving spool the used length of blade. The device as proportioned provides on the supply spool a sufficient length of blade to last the average person a full year. After the supply of blade on the supply spool is exhausted, the casing section 31 may be displaced by removing the screws 55 and 68. The terminal 22 attached to the supply spool is released and wound upon the receiving spool, which may then be discarded. The original supply spool is then shifted and becomes the receiving spool, and a new supply spool is emplaced on the tubular boss 44 and the casing section 31 re-applied.

If desired, the assemblage 63 may include a separate manipulator or key 100 which is provided with a threaded opening 101 adapted to engage with a threaded shank 102 formed on and projecting upwardly from the circular head 64 of the spool mounting and turning assemblage. The manipulator or key thus serves in the capacity of a means for preventing unauthorized feeding of a fresh length of blades by others, in that when it is unscrewed and removed, the circular head 64 and threaded shank 102 cannot be employed for turning the assemblage. Furthermore, the threaded or equivalent con-

nection of the manipulator with the receiving spool mounting and turning assemblage 63 serves to prevent retrograde turning of the assemblage, with the possibility of damage to the ratchet pawl, ratchet teeth, the coupling between the spool and its mounting or other parts. It is obvious that retrograde turning of the manipulator or key 100 will immediately effect the unscrewing of the same, thus protecting the parts against straining or breakage.

In some instances, however, it may be found desirable to totally discard the holder when the blade supply is exhausted, and in this case the casing sections 30a and 31a are permanently fastened together by the dovetail notches 30b and lugs 31b. In this instance, the lower casing section 31a is provided with inwardly offset bosses 31c and 31d, the former fitting into the tubular boss 44a and the latter acting as a journal for the receiving spool and having riveted thereto as at 31e, the terminal of the shank 66a of the receiving spool mounting member.

25 What is claimed is:

1. In a safety razor having a continuous blade, a blade holder fashioned to provide a hollow handle part to contain the unused and used lengths of the blade and a guard part defining a pair of spaced flat non-parallel surfaces for simultaneously supporting for shaving, two separate lengths of the blade.

2. In a safety razor having a continuous blade, a blade holder fashioned to provide a hollow handle part to contain the unused and used lengths of the blade and a guard part defining a pair of spaced flat non-parallel surfaces for simultaneously supporting for shaving, two separate lengths of the blade and a clamping element carried by and shiftable with respect to the holder to releasably clamp the two active blade lengths between the same and said surfaces.

3. In a safety razor having a continuous blade, a blade holder fashioned to provide a hollow handle part to contain the unused and used lengths of the blade and a guard part defining a pair of spaced flat non-parallel surfaces for simultaneously supporting for shaving, two separate lengths of the blade, a clamping element carried by and shiftable with respect to the holder to releasably clamp the two active blade lengths between the same and said surfaces and means in said handle part for supporting in coiled form, the used and unused lengths of the blade.

4. A safety razor having the combination of a continuous blade, a supply spool upon which the unused length of the blade is coiled, a receiving spool upon which the used length of the blade is coiled and a blade holder fashioned to provide a closed hollow handle part to contain said spools and a guard part defining a pair of spaced flat non-

parallel surfaces for simultaneously supporting for shaving, two separate lengths of the blade.

5. A safety razor having the combination of a continuous blade, a supply spool upon which the unused length of the blade is coiled, a receiving spool upon which the used length of the blade is coiled and a blade holder fashioned to provide a closed hollow handle part to contain said spools and a guard part defining a plurality of spaced flat non-parallel surfaces for simultaneously supporting for shaving, a plurality of separate lengths of the blade.

6. A safety razor having the combination of a continuous blade, a supply spool upon which the unused length of the blade is coiled, a receiving spool upon which the used length of the blade is coiled and a blade holder fashioned to provide a closed hollow handle part to contain said spools and a guard part defining a plurality of spaced flat non-parallel surfaces for simultaneously supporting for shaving, a plurality of separate lengths of the blade and means within said handle part for mounting the blade spools for turning movement.

7. A safety razor having the combination of a continuous blade, a supply spool upon which the unused length of the blade is coiled, a receiving spool upon which the used length of the blade is coiled and a blade holder fashioned to provide a closed hollow handle part to contain said spools and a guard part defining a plurality of spaced flat non-parallel surfaces for simultaneously supporting for shaving, a plurality of separate lengths of the blade and means within said handle part for mounting the blade spools for turning movement and for limiting turning movement thereof in a direction to feed the unused length of the blade over the guard part from the supply spool and for winding the used part onto the receiving spool.

8. A safety razor having the combination of a continuous blade, a supply spool upon which the unused length of the blade is coiled, a receiving spool upon which the used length of the blade is coiled and a blade holder fashioned to provide a closed hollow handle part to contain said spools and a guard part defining a plurality of spaced flat non-parallel surfaces for simultaneously supporting for shaving, a plurality of separate lengths of the blade, means for mounting the blade spools for turning movement and for limiting turning movement thereof in a direction to permit of the feeding of the unused length of the blade over the guard part, said means being engageable with the receiving spool, to effect turning thereof to wind the blade thereon for feeding said blade from the supply spool over the guard part and an exteriorly disposed removable manipulator formed as a part of said means.

9. A safety razor having the combination of a continuous blade, a supply spool upon which the unused length of the blade is coiled, a receiving spool upon which the used 5 length of the blade is coiled and a blade holder fashioned to provide a closed hollow handle part to contain said spools and a guard part defining a plurality of spaced flat non-parallel surfaces for simultaneously supporting for 10 shaving, a plurality of separate lengths of the blade, means for mounting the blade spools for turning movement and for limiting turning movement thereof in a direction to permit of the feeding of the unused 15 length of blade over the guard part, said means being engageable with the receiving spool, to effect turning thereof to wind the blade thereon for feeding said blade from the supply spool over the guard part and an 20 exteriorly disposed removable manipulator formed as a part of said means and having a connection which is releasable upon retrograde turning movement.
10. A safety razor having the combination 25 of a continuous blade, a supply spool upon which the unused length of the blade is coiled, a receiving spool upon which the used length of the blade is coiled and a blade holder fashioned to provide a closed hollow handle part 30 to contain said spools and a guard part defining a plurality of spaced flat non-parallel surfaces for simultaneously supporting for shaving, a plurality of separate lengths of the blade, means for mounting the blade 35 spools for turning movement and for limiting turning movement thereof in a direction to permit of the feeding of unused lengths of blade over the guard part and cooperative coupling devices provided on the receiving 40 spool and its mounting including correspondingly shaped inter-engaging portions thereof.
11. A safety razor having the combination 45 of a continuous blade, a supply spool upon which the unused length of the blade is coiled, a receiving spool upon which the used length of the blade is coiled and a blade holder fashioned to provide a closed hollow handle part to contain said spools and a guard part defining a pair of spaced flat longitudinally converging 50 surfaces joined at their outer ends by a curved connecting surface and coinciding respectively at their inner ends with blade passages communicating with the hollow handle part, said flat surfaces constituting means for simultaneously supporting for shaving, two 55 separate lengths of the blade.
12. A safety razor having the combination 60 of a continuous blade, a supply spool upon which the unused length of the blade is coiled, a receiving spool upon which the used length of the blade is coiled and a blade holder fashioned to provide a closed hollow handle part to contain said spools and a guard part defining a pair of spaced flat longitudinally converging 65 surfaces joined at their outer ends by a curved connecting surface and coinciding respectively at their inner ends with blade passages communicating with the hollow handle part, said flat surfaces constituting means for simultaneously supporting for shaving, two separate lengths of the blade.
13. A safety razor including in combination a continuous blade having a longitudinal cutting edge, a supply spool upon which the blade is wound, a receiving spool upon which the used blade is adapted to be wound and a combined blade holder and handle including a hollow casing within which the spools are housed and rotatably mounted in the same plane, an extension on said casing constituting a guard around which the blade is trained, said extension having a pair of oppositely disposed straight sides converging longitudinally and joined by a curved surface and a correspondingly shaped clamping element carried by the casing and shiftable with reference to the extension to clamp or release the blade.
14. A safety razor including in combination a continuous blade having a longitudinal cutting edge, a supply spool upon which the blade is wound, a receiving spool upon which the used blade is adapted to be wound and a combined blade holder and handle including a hollow casing within which the spools are housed and rotatably mounted in the same plane, an extension on said casing constituting a guard around which the blade is trained, said extension having a pair of oppositely disposed straight sides converging longitudinally and joined by a curved surface and a correspondingly shaped clamping element carried by the casing and shiftable with reference to the extension to clamp or release the blade.
15. In a safety razor, the combination of a blade holder having a hollow handle and a guard portion extending from one end of the handle, said guard portion being so constructed and arranged as to provide a pair of flat longitudinally converging side faces joined by a curved surface at their outer ends; of a continuous blade coiled within the handle and trained around the convergent side faces and curved surface of the guard portion to expose two lengths of the blade for use.
16. In a safety razor, the combination of a blade holder having a hollow handle and a guard portion extending from one end of the handle, said guard portion being so constructed and arranged as to provide a pair of flat longitudinally converging side faces joined

by a curved surface at their outer ends; of a continuous blade coiled within the handle and trained around the convergent side faces and curved surface of the guard portion to expose 5 two lengths of the blade for use and a co-operative blade clamping element mounted on the handle for shifting movement to clamp or release the blade.

17. A safety razor having the combination 10 of a continuous blade, a supply spool upon which the unused length of the blade is coiled, a receiving spool upon which the used length of the blade is coiled and a blade holder fashioned to provide a closed hollow 15 handle part to contain said spools and a guard part defining a plurality of spaced flat non-parallel surfaces for simultaneously supporting for shaving, a plurality of separate lengths of the blade, means for removably 20 mounting the blade spools for turning movement and for limiting turning movement thereof in a direction to permit of the feeding of the unused length of blade over the guard part and means for variably retarding the turning of the supply spool.

18. In a continuous blade for safety razors having a longitudinal cutting edge and adapted to be coiled on a flanged spool, terminals at the opposite ends of the blade constituting 30 means for spacing the cutting edge from the spool flange to prevent contact of said cutting edge therewith.

19. In a continuous blade for safety razors having a longitudinal cutting edge and adapted to be coiled on a flanged spool, terminals at the opposite ends of the blade constituting 35 means for spacing the cutting edge from the spool flange to prevent contact of said cutting edge therewith and functioning as a means for handling the blade and connecting the same with the spool.

20. In a continuous blade for safety razors having a longitudinal cutting edge and adapted to be coiled on a flanged spool, terminals at the opposite ends of the blade constituting 45 means for spacing the cutting edge from the spool flange to prevent contact of said cutting edge therewith and functioning as a means for handling the blade and connecting the same with the spool, said terminals consisting of a strip of material of greater width than the blade.

21. A spool for a continuous safety razor 55 blade, said spool including a cylindrical body and flanges at the opposite ends of said body, one of said flanges being transparent to display the amount of blade on the spool.

22. A spool for a continuous safety razor 60 blade having sharpened and unsharpened opposite longitudinal edges, said spool including a cylindrical body and flanges at the opposite ends of said body, one of said flanges being magnetized to cause the un- 65 sharpened edge to adhere thereto, whereby

to maintain the sharpened edge out of contact with the other flange.

23. A spool for a continuous safety razor blade having sharpened and unsharpened opposite longitudinal edges, said spool including a cylindrical body and flanges at the opposite end of the body and means for causing the unsharpened edge to adhere to one flange so as to maintain the sharpened edge out of contact with the other flange.
